CLAIM

The ornamental design for a hair styling iron, as shown, and described.

DESCRIPTION

FIG. 1 is a perspective view of the hair styling iron;
FIG. 2 is a right side view of the hair styling iron;
FIG. 3 is a left side view of the hair styling iron;
FIG. 4 is a top view of the hair styling iron;
FIG. 5 is a bottom view of the hair styling iron;
FIG. 6 is a front view of the hair styling iron; and,
FIG. 7 is a rear view of the hair styling iron.
The broken lines depicting a styling iron handle form no part of the claimed design.
